Inventor:

Felix Rodgers

United States Patent Office.

FELIX RODGERS, OF PHILADELPHIA, PENNSYLVANIA.

Design No. 3,969, dated April 12, 1870.

DESIGN FOR SHADE FOR GAS-LIGHTS, &c.

The Schedule referred to in these Letters Patent and making part of the same.

I, FELIX RODGERS, of the city of Philadelphia, in the State of Pennsylvania, have invented and produced a new and original Design for Glass Shades for Gas and other Lights, of which the following is a specification.

The nature of my design consists in the exterior shape or form represented in the accompanying drawing, showing a vertical central section of the said shade, and to which reference is made.

The shade is circular in its transverse or horizontal

section, and its sides are of the shape or form shown from *a* to *b* in the drawing.

Claim.

I claim as my invention—

The design for a glass shade, as shown.

FELIX RODGERS.
